ATTORNEY

UNITED STATES PATENT OFFICE

HENRY J. GAISMAN, OF NEW YORK, N. Y., ASSIGNOR TO AUTOSTROP PATENTS CORPORATION, OF DOVER, DELAWARE, A CORPORATION OF DELAWARE

SAFETY RAZOR

Application filed November 10, 1927, Serial No. 232,221. Renewed February 18, 1929.

One of the objects of my invention is to provide a safety razor in which a guard for a blade and a roller for causing operation of a blade holder for sharpening the blade edge may be folded in a compact relation to the main frame of the razor, for storage and transportation, arranged in such a way that when the parts are in the position stated and the roller is reciprocated along a sharpening surface the blade may be rocked for sharpening its edge, and whereby when the razor is to be used for shaving the guard and the roller may be moved relatively to the frame to present the guard in shaving position respecting the blade, and whereby the roller may be manipulated for operating the guard.

Another object is to provide means operative with the guard for moving the blade from the folded position to a position adapted for engagement with the guard while the guard is being moved to shaving position to assure the proper location of the guard and the blade relatively to each other without requiring the blade to be operated directly by hand for such purpose.

My invention also comprises novel details of improvement that will be more fully hereinafter set forth and then pointed out in the claims.

Reference is to be had to the accompanying drawings forming a part hereof, wherein—

Fig. 1 is a side view of a safety razor embodying my invention, showing the parts in shaving position;

Fig. 2 is a vertical section of Fig. 1, showing the parts in folded position;

Fig. 3 is a view partly in section looking from the left hand side of Fig. 2;

Fig. 4 is a detail perspective view;

Fig. 5 is a section on line 5, 5, in Fig. 12;

Figs. 6 and 7 are diagrammatic views showing the parts in different positions;

Figs. 8 and 9 are side views of the blade holder showing parts in different positions;

Fig. 10 is a section on line 10, 10, in Fig. 3;

Fig. 11 is a section on line 11, 11, in Fig. 8, 50 and

Fig. 12 is a view illustrating the razor in stropping position.

Similar numerals of reference indicate corresponding parts in the several views.

The frame 1 of the razor may be of any suitable construction, the same being shown comprising a base 1^a and spaced uprights 1^b, to which base a handle 2 may be attached in any suitable way, such as by riveting. At 3 is indicated a guard for the blade 4, which guard is shown supported by spaced arms 5, which arms are pivotally supported at 6 between and on the uprights 1^b. The guard 3 and the arms 5 may be made from a single piece of material bent to shape, and the parts are so arranged that the guard may fold between the uprights 1^b, (Fig. 3). A projection 7 on an upright 1^b is adapted to enter a hole 8 in the adjacent arm 5 to retain the latter and the guard folded in the razor frame, as in Fig. 2, said projection being adapted to engage a hole 9 in said arm when the arms and the guard are in shaving position to retain the guard relatively to the blade. Hook-like stops 10 adjacent to the corners of the guard are adapted to extend over the blade to retain the latter upon the guard when the parts are in shaving position, (Fig. 1). A roller 11 is journaled on and between the arms 5 at their ends opposite the guard 3, and thereby the roller is connected with the guard, which roller may be used as a finger piece for manipulating the arms and the guard. A blade holder is indicated at 12, which blade holder is shown comprising a plate 12' provided with pivots 13 journaled in holes in the uprights 1^b, whereby the blade holder is pivotally supported to swing between said uprights. The pivots are shown extending from ears 14 that may be pressed out from the metal of plate 12' and turned laterally respecting the plate. The pivots 13 are shown provided with gears 15 that are adapted to engage corresponding gears 16 secured to the roller 11, (Fig. 4), whereby when the parts are folded, as illustrated in Figs. 2 and 3, with the roller adjacent to the blade holder, the gears 15 and 16 will intermesh, so that when roller 11 is applied upon a sharpening or stropping sur-

85

face 17 and is reciprocated along said surface the roller will be rotated for rocking the blade holder through the frame and the arms to present opposite sides of the edge of the blade to said surface for sharpening the blade edge. When the arms 5 are turned from the position shown in Fig. 2, as to the shaving position shown in Fig. 1, the guard will be moved to one side of the uprights 1^b of the main frame and the roller 11 will be moved to the opposite side of said frame. At such time the gears 15 and 16 will be disconnected.

Since the blade holder and the blade may fold within the frame, as in Figs. 2 and 3, it is desirable to automatically move said blade holder with the blade outwardly respecting the frame when the arms 5 are moved from the folded position toward the shaving position. For such purpose I provide a blade holder adjuster 18, which is shown in the form of a bent arm, pivotally supported upon and within one of the uprights 1^b, at 19, in position between said uprights and the adjacent arm 5, which adjuster has a lateral projection 18' adapted to engage the blade holder to push it laterally from the frame when the arms 5 are swung away from the folded position of Fig. 2. To operate the blade holder adjuster 18 the same is shown provided with a laterally disposed pin 20 which is operative in an irregularly shaped slot 21 in the adjacent arm 5. One portion 21^a of slot 21 is substantially concentric with the pivot 6 and the other portion 21^b of said slot is disposed angularly with respect to said pivot. When the parts are in the folded position, (Figs. 2 and 6), the pin 20 will be in the outer part of the angular portion 21^b of slot 21. When the arms 5 are rotated the action of an arm 5 against pin 20 will be to cause the blade holder adjuster 18 to move toward the blade holder causing the projection 18' of the adjuster to engage the blade holder and push it outwardly at the time that the guard 3 is rising respecting the blade, in such a way that the edge portion of the blade will be raised beyond the arc of rotation of the inner portion of the guard, substantially as indicated in Fig. 7. During further movement of the guard toward shaving position the arcuate portion 21^a of slot 21 will cause the actuator 18 to come to rest and the guard will engage the blade and lift it so that when the guard and blade are in shaving position the stops 10 will be upon the blade and the latter and the guard will be retained for shaving, (Fig. 1). When the arms 5 are rotated to the folded position the slot 21 will reversely operate the adjuster 18 so as to remove its projection 18' from the blade holder to permit the latter to swing to the folded position. In order that the blade holder may operate freely through the main frame and between the arms 5, during

stropping, the blade holder plate 12' is provided with a notch or recess at 12^a in position to register with the projection 18' when the parts are in the folded and stropping position of Fig. 2, so that said projection will not interfere with the blade holder for stropping.

The blade holder may be provided with any desired means for detachably retaining the blade 4. In the example illustrated the blade holder plate 12' is provided with spaced projections 22, (Figs. 3 and 8), adapted to enter openings 23 in the blade to retain the latter from shifting upon the plate, and a jaw-like member 24 is pivotally supported at 25 on plate 12', whereby the jaws are adapted to receive plate 12' and the blade to retain the latter in shaving relation, (Figs. 2, 3 and 10). When the member 24 is swung away from the blade the latter may be released and be replaced, (Fig. 9).

When it is desired to strop the blade edge the parts are assembled, as in Fig. 2, and the razor is presented to the sharpening surface, as indicated in Fig. 12, with the roller 11 bearing upon said surface. When the razor is reciprocated along surface 17 the engagement of roller 11 therewith will cause rotation of the roller and by means of the meshing gears 15 and 16 the blade holder and the blade will be rocked to present opposite edges of the blade against said surface for sharpening the edge during reciprocation of the razor, in a known way. When the blade is to be used for shaving the roller 11 may be moved outwardly to cause the arms 5 to rock to operate the adjuster 18 and assemble the guard and blade, as in Fig. 1. To release the guard from the blade the roller 11 may be pushed toward the outer portion of the main frame, whereupon the adjuster will be withdrawn from the blade holder and the parts may be folded within the frame, as in Fig. 2.

Changes may be made in the details of construction and the arrangement of parts set forth, within the scope of the appended claims, without departing from the spirit of my invention.

Having now described my invention what I claim is:—

1. A safety razor comprising a frame, a guard and a roller connected together and pivotally carried by the frame, a blade holder pivotally carried by the frame, and cooperative means between the roller and the blade holder for rocking the latter when the guard is away from the blade and the roller is adjacent to the blade holder.

2. A safety razor as set forth in claim 1, provided with means operative with the roller to actuate the blade holder to locate a blade in position to cooperate with the guard in shaving position of the parts.

3. A safety razor comprising a frame, arms pivotally carried by the frame, a guard

connected with said arms on one side of the pivots, a roller connected with the arms on the opposite side of the pivots, a blade holder pivotally carried by the frame, a gear connected with the blade holder, and a gear connected with the roller, said gears being so located as to mesh when the roller is adjacent to the blade holder and the guard is away from the blade.

4. A safety razor as set forth in claim 3, provided with an adjuster operative by one of said arms to move the blade holder and blade into position for assembly of the blade and the guard for shaving.

5. A safety razor as set forth in claim 3, provided with an adjuster pivotally carried by the frame adapted to move the blade holder outwardly relatively to the frame, and means cooperative between one of said arms and said adjuster for actuating the latter.

6. A safety razor as set forth in claim 3, provided with an adjuster pivotally carried by the frame adapted to move the blade holder outwardly relatively to the frame, one of said arms having a slot, the adjuster having a pin operative in the slot for moving the blade holder with a blade into position for assembly of the blade and the guard for shaving.

7. A safety razor as set forth in claim 3, provided with an adjuster pivotally carried by the frame adapted to move the blade holder outwardly relatively to the frame, one of said arms having a slot, a portion of which slot is concentric with the axis of the arm and another portion of which slot is at an angle to said axis for moving the blade holder with a blade into position for assembly of the blade and the guard for shaving.

8. A safety razor comprising a frame, a pair of spaced arms pivotally carried by the frame, said arms having a guard at one end and a roller at the opposite end, a blade holder pivotally carried by the frame and adapted to rock between said arms, said blade holder having a gear, and a gear connected with said roller, said gears being arranged to mesh when the roller is adjacent to the blade holder, whereby the roller may cause rocking of the blade holder when the guard is away from the blade.

9. A safety razor as set forth in claim 8, provided with an adjuster pivotally carried by the frame, said adjuster having a laterally disposed projection adapted to engage the blade holder, and means cooperative between the adjuster and one of said arms for causing said projection to operate the blade holder for assembling the guard and blade for shaving when the arms are rotated with the roller in a direction away from the blade holder.

10. A safety razor as set forth in claim 8, in which the blade holder is provided with a recess to permit the passage of the projec-

tion of the adjuster when the blade holder is folded within the frame.

11. In a safety razor, a frame, a blade holder oscillatively mounted thereon, the said frame having a clearance for the blade and holder, a guard mounted for movement with respect to the frame into and out of operative relation to the blade, a rotative member carried by the guard and adapted to be turned when moved in contact with a surface, and means for imparting the motion of the rotative member to the blade holder.

12. In a safety razor, a frame, a blade holder oscillatively mounted thereon, the said frame having a clearance for the blade and holder, a guard mounted for movement with respect to the frame into and out of operative relation to the blade, a rotative member carried by the guard and adapted to be turned when moved in contact with a surface, means for imparting the motion of the rotative element to the blade holder, and means for mounting the guard for movement to co-operate with the blade or to operatively correlate the rotative element and the blade holder.
